Chen, B., "Marker," U.S. Appl. No. 29/384,492, filed Jan. 31, 2011.

Primary Examiner — Elizabeth Albert(74) *Attorney, Agent, or Firm* — Christensen O'Connor Johnson Kindness PLLC**(57) CLAIM**

The ornamental design for a marker, as shown and described.

DESCRIPTION

FIG. 1 is an upper front right perspective view of a marker showing my new design;

FIG. 2 is a front elevation view thereof, with the rear, right side, and left side elevation views being a mirror image of the front elevation view;

FIG. 3 is an enlarged top plan view thereof; and,

FIG. 4 is an enlarged bottom plan view thereof.
